FRED BODENSTEIN AND JOHN G. BODENSTEIN, JR., OF STAATSBURG, NEW YORK.

ROAD-RESURFACING MACHINE.

Application filed April 22, 1927. Serial No. 185,740.

The invention aims to provide a new and improved machine for cutting off frozen snow or ice between parallel ruts on a road and along the outer sides of said ruts, the construction being such that the frozen material will be cut off substantially even with the rut bottoms and will be thrown to one side, out of the way.

With the foregoing in view, the invention resides in the novel subject matter herein-after described and claimed, the description being supplemented by the accompanying drawings.

Fig. 1 is a perspective view of a machine constructed in accordance with our invention.

Fig. 2 is a vertical longitudinal sectional view.

Fig. 3 is a vertical transverse section on line 3—3 of Fig. 2.

Fig. 4 is a fragmentary perspective view looking at one rear corner of the machine.

Figs. 5 and 6 are diagrams showing the condition of the road before and after use 25 of the machine thereon.

The drawings above briefly described, illustrate the preferred form of construction and while this construction will be herein-after specifically described, it is to be understood that within the scope of the invention 30 as claimed, variations may be made.

A frame is shown embodying two longitudinally disposed side bars 7 which are laterally spaced a distance corresponding to the 35 gauge of vehicle wheels, so that said bars may travel in and be guided by parallel ruts in frozen snow or ice upon a road. The front ends of these bars preferably curve upwardly as indicated at 8 and said bars are provided with suitable supporting shoes 40 9 and 10 at their front and rear ends. Two short lengths of angle metal stock 11, are secured by bolts 12 to the front portions of the side bars 7 and project upwardly therefrom, and a pair of transverse bars 13 are secured by bolts 14 to the members 11, establishing effective tie means between the front 45 ends of the aforesaid bars. Preferably, the bolts 14 also secure a pair of draft bars 15 in place, the front ends of said bars having hooks 16 to be engaged by suitable draft means. Also, some of the bolts 14 may be utilized to anchor an arched foot-rest 17 which is 50 disposed in advance of an appropriate seat 18, said seat having supporting legs 19 bolted to the side bars 7. Three transverse bars

20, 21 and 22 have been shown extending between and suitably secured to the side bars 7, said bars being disposed at progressively lowered positions from the front toward the rear of the machine. These bars are provided with forwardly declined spikes or teeth 20^a, 21^a and 22^a respectively, secured thereto in any desired manner, and all of these teeth may well be formed from tempered tungsten steel for effective ice cutting. As shown most clearly in Fig. 2, the spikes or teeth 20^a, 21^a and 22^a are disposed at progressively lower positions from the front toward the rear of the machine. Thus, they will remove individual "slices" of the frozen material between the ruts, and the last or rear set of teeth is so positioned that said material will be cut off substantially flush with the bottoms of the ruts, as will be clear from Fig. 6. 75

Suitably secured to and projecting laterally from the side bars 7, preferably near their rear ends, are two tooth or spike-carrying members 23 which are provided with forwardly declined spikes or teeth 23^a, 80 adapted to cut off the frozen material along the outer sides of the ruts, substantially even with the rut bottoms, the cutting however, being done in an inclined plane, as will be clear from Figs. 3 and 6. Braces 24 are provided for these members 23, said braces having front portions 24^a which extend inwardly toward the side bars 7 and have downturned inner ends secured by bolts or the like 24^b, to said side bars 7. These 85 braces not only act to hold the members 23 against rearwardly springing, but they also perform an additional function hereinafter described and act also as guards to prevent the operator from being cut by the teeth 23^a. 95

Suitable shoes 25 are provided at the rear ends of the runners or side bars 7, said shoes being carried by longitudinal levers 26, fulcrumed to the members 7 as indicated at 27. Normally, the front ends of these levers lie 100 upon the transverse portion 24^a of the braces 24 and hence are held against digging into the frozen material along the road. Whenever advisable, one or both of these levers may be pulled upwardly and hooked behind 105 appropriate lugs 28 on the ends of the seat 18. This movement of the levers causes the shoes 25 to engage the bottoms of the ruts and consequently effects elevation of the rear portion of the machine, which is often 110 necessary when obstructions are encountered.

For the purpose of throwing the greater part of the loosened frozen material, laterally from the roadway, we prefer to provide a scraper blade 29 disposed behind the machine. One end of this blade may well have suitable bearings 30 receiving an upstanding shaft 31 whose lower end is appropriately secured at 32 to one of the side bars 7. The blade 29 is preferably connected by a coil spring 33 with a suitable anchor 34 secured to the other side bar 7, permitting said blade to yield rearwardly whenever it engages an obstruction.

A machine constructed as or substantially as herein shown and described, will be very efficient for the purposes intended, and will so resurface a road covered by frozen material, as to permit more expeditious travel. When a pair of ruts are formed in a road and machines travel continually in them, it is very often practically impossible to cut out of these ruts when one machine is to pass another and this causes not only trouble and inconvenience but very often accidents. By the use of the invention however, the roadway is given substantially the transverse shape shown in Fig. 6 and hence difficulties are effectively overcome.

Within the scope of the invention as claimed, various modifications may be made. For instance, in some cases, supporting wheels might be used for the frame structure, spaced apart a distance to travel in the ruts. Moreover, the specific construction and anchorage of the ice cutting teeth may be varied as occasion may demand, although we prefer, at least for the two rear sets of teeth 21^a—22^a, to use steel stock which is square in transverse section, said stock being cut to desired lengths and doubly beveled at one end to provide for the ice cutting, the beveling being so done that when the teeth are clamped or otherwise held in place, their points will decline forwardly as shown most clearly in Fig. 2.

We claim:

1. A machine for resurfacing a frozen snow or ice covered road having parallel ruts formed therein by vehicle wheels; said machine comprising a frame having supporting means laterally spaced a distance corresponding to the gauge of vehicle wheels, whereby said supporting means may travel in the ruts and be guided thereby, means carried by the frame for cutting off the frozen material between the ruts substantially even with the bottoms of the latter, and means carried by said frame for cutting off the frozen material along the

outer sides of the ruts substantially even with said bottoms thereof.

2. A machine for resurfacing a frozen snow or ice covered road having parallel ruts formed therein by vehicle wheels; said machine comprising a pair of parallel side members spaced apart a distance corresponding to the gauge of vehicle wheels, whereby said side members may travel in and be guided by the ruts, transverse members extending between and secured to said side members, cutters on said transverse members for cutting off the frozen material between the ruts substantially even with the bottoms thereof, rigid members secured to and projecting laterally outward from said side members, and cutters on said lateral members for cutting off the frozen material at the outer sides of the ruts substantially even with the rut bottoms.

3. A machine for resurfacing a frozen snow or ice covered road having parallel ruts formed therein by vehicle wheels; said machine comprising a frame having supporting means laterally spaced a distance corresponding to the gauge of vehicle wheels, said frame embodying a plurality of transverse bars to extend across the road between the ruts, said bars being disposed at different heights with the highest toward the front of the machine and the lowest toward the rear thereof, and a plurality of forwardly declined teeth secured to each of said bars, the front ends of said teeth being disposed at progressively lower elevations from the front toward the rear of the machine.

4. In a machine for resurfacing a frozen snow or ice covered road having ruts formed therein by vehicle wheels; a longitudinal member to travel in a rut, a lateral member secured to said longitudinal member and having cutting means for cutting off the frozen material along one side of the rut, a shoe at the rear end of the longitudinal member, a longitudinal lever carrying said shoe and fulcrumed to said longitudinal member whereby upon upward swinging of said lever the rear end of said longitudinal member will be raised, and a brace for said lateral member extending forwardly and inwardly therefrom, the inwardly extending portion of said brace normally underlying said lever to support the latter in inoperative position.

In testimony whereof, we have hereunto affixed our signatures.

FRED BODENSTEIN.

JOHN G. BODENSTEIN, Jr.
